UNITED STATES PATENT OFFICE.

STEVE BOROS, OF KENMORE, OHIO.

DESIGN FOR A TABLE STAND.

Application filed April 6, 1925. Serial No. 13,032. Term of patent 7 years.

To all whom it may concern:

Be it known that I, STEVE BOROS, a citizen of the Republic of Hungary, residing at Kenmore, in the county of Summit and State of Ohio, have invented a new, original, and ornamental Design for Table Stand, of which the following is a specification, reference being had to the accompanying drawings, forming a part hereof.

The figure is a perspective view showing my new, original and ornamental design for table stand.

I claim:

The ornamental design for a table stand as shown.

STEVE BOROS.

Witnesses:

JERRY FORTE,
FRIEDA FRITSCH.
